UNITED STATES PATENT OFFICE.

HENRY C. CURRIER, OF MILLERS FALLS, MASSACHUSETTS.

SNUBBING MACHINE.

Application filed November 26, 1921. Serial No. 517,878.

To all whom it may concern:

Be it known that I, HENRY C. CURRIER, a citizen of the United States, residing at Millers Falls, in the county of Franklin and State of Massachusetts, have invented a certain new and useful Improvement in Snubbing Machines, of which the following is a specification.

My present invention relates to that type of machines which are used for controlling the movement of load sustaining cables and the invention especially relates to that class of machines shown in my Letters Patent No. 1,273,745 issued July 23, 1918.

The present invention has for its objects to provide a simply constructed machine of the character whereby the movement of a cable for snubbing logs on an inclined plane is controlled; to provide a snubbing machine having a series of drums and pulleys upon which a snubbing cable is threaded whereby the cable is controlled; to provide, in a snubbing machine, a series of drums and a series of pulleys mounted upon an inclined support, whereby the snubbing cable is guided upon said drums; to provide, in a snubbing machine, a pair of drums over which the snubbing cable operates and means for braking one of said drums and releasing the other drum automatically and vice versa; to provide, in a snubbing machine, a drum shaft and means for controlling the rotation of said shaft; and to provide, in one embodiment of my invention, a means for manually operating the machine.

The invention in its more detailed nature also resides in those novel features of construction, combination and arrangement of parts, all of which will be first fully described and then be specifically pointed out in the appended claims, reference being had to the accompanying drawings, in which:

Figure 1 is a side elevation of the preferred embodiment of my invention.

Figure 2 is a top plan view of the same.

Figure 3 is a front elevation thereof.

Figure 4 is a rear elevation thereof.

Figure 5 is a cross section on the line 5—5 of Figure 2.

Figure 6 is a top plan view of another embodiment of the invention.

Figure 7 is a side elevation, on a reduced scale, of the mechanism shown in Figure 6.

Figure 8 is a front elevation of the mechanism shown in Figure 7.

Figure 9 is a cross section on the line 9—9 of Figure 7.

Figure 10 is a rear elevation of the construction shown in Figure 7.

In the drawings in which like numerals 60 of reference designate like parts in all of the figures, 1 represents the longitudinal beams of the sled which carries the mechanism, the beams 1 having skids 2 and being connected together by cross beams 29 and 34. 65 A bail 3 is provided for towing purposes and also to serve as a convenient means of connection with a suitable anchorage.

Mounted in a suitable bearing 4 on the beams 1 is a drum shaft 5 on which is 70 mounted a cable drum 6 having a plurality of cable receiving grooves and having a brake disk 7 around which the brake band 21—22 passes.

A rod 8 is held in a bearing 9 and a guide 75 10 and is secured to link plates 13 which have a series of holes 15 for purposes of adjustably connecting the same to the treadle or foot lever 12. The lever 12 is mounted on the rod 11 and the plates 13 are 80 secured to the lever by bolts and nuts 14. A guide 16 with a strap 17 having key or pin holes 18 for a holding pin 19 serves to hold the lever 12 in any one of a series of positions whereby different degrees of braking stress 85 may be applied to the brake disk 7 of the drum; the lever has a loop 20 to serve as a foot guard or as a handle as may be desired.

The brake band consists of two sections 21—22, the former being secured to the rod 90 8 at one of its ends and the latter being secured at its corresponding end to the rod 11, the two brake band sections being connected by bolts and nuts 25—26 respectively to one another through the use of link plates 23 95 having a series of holes 24 for purposes of adjustment and taking up wear.

Mounted on a stepped shaft 27—28 are a number of pulleys 31 over which and around the drum 6 the cable passes, the shaft 27 100 being braced by eye bolts 30 from the cross beam 29.

Standards 32—32 are sustained on the cross beams 34 and are united, at their tops, by a cross beam 33 thereby constituting a 105 frame to sustain the front or tension drums and the devices for pressing the cable on the same, i. e. for braking the drums alternately. Mounted in bearings 35 on the standards 32 are shafts 36 for the two grooved drums 37, 110

each of which drums has a brake hub 38, see Figure 5, by reference to which it will also be observed that I provide two U-frames 39 having slots 40 through which lag screws 41 pass to hold the U-frames vertically slidable on the standards 32. The U-frames are normally held down under spring tension by rods 42 which are connected at 43 to the U-frames 39, pass through guide 10 openings 44 in the beam 33 and through holes 45 in a bar 46, the latter being adjustable on bolts 47 through the medium of nuts 49 so as to vary the tension on the springs 48 which are interposed between the bar 46

15 and the attachment 43. The springs 48 tend to hold the U-frames 39 downwardly to thereby hold the rollers 50 in the grooves of the drums 37 and in contact with the cable 75 for a purpose presently understood. 20 The rollers 50 are each mounted on a shaft 51 journaled in bearings in the U-frames 39. By adjusting the nuts 49 up or down, the normal tension of the springs 48 can be adjusted.

25 This construction just described allows the rollers 50 to rise when knots or splices in the cables pass between rollers 50 and the drums 37.

50 52 designate brake bands, one end of each of which is held around the shafts 51 as at 53 and the other end 54 is carried by rods 55 which pass through slots 56 in the cross beam 33 and are pivoted at 57 to a lever 58 which is fulcrumed at 59 on a bolt 60. The bolt 35 60 passes into the beam 33 in which it is guided and a spring 61 serves to thrust the bolt 60 up to thereby hold the lever 58 with its fulcrum 59 in position. The lever 58 passes through a guide 62 having pin holes 40 63 through which a stop or holding pin 64 (see Figure 1) may be passed to maintain the lever in its tilted positions.

At the front of the machine are horizontal guide rolls 65 and vertical guide rolls 66 suitably mounted to guide the cable to the drums 37.

In the embodiment of my invention just described, the cable passes over one of the guide rolls 65, thence between a pair of guide 50 rolls 66, thence around a drum 37, thence alternately around the grooves of the drum 6 and the pulleys 31 and back over the second drum 37 and thence between the second pair of guide rolls 66 and over the second horizontal guide roll 65.

60 In Figures 6 to 9, inclusive, I have shown another embodiment of my invention. In those figures the parts having the same function and being of the same general construction as corresponding parts in the preceding figures, bear the same reference number plus the index letter "x." In this form of the invention, the brake bands 52^x have one end fastened to a rod 67 from which they 65 pass up over the hubs 68 of the rollers 60^x,

thence down around the brake hubs 38^x, the other ends being secured to the rods 55^x. The lever 58^x also is held by an upper spring 61 and a lower spring 61^x, it having its fulcrum on rods 60^x between the two springs 68 70 and 61^x. In this form also two drums 6^x—6^x are employed as in my patent before referred to. Each drum has grooved brake disks 7^x around which the brake band 21^x is passed, the band 21^x having its end anchored at 69 75 and being drawn taut to apply friction whenever lever 12^x is pushed down by pressure of rod 8^x on the band 21^x between the two disks 7^x.

80 Provision may also be made for operating the drums 6^x by hand, if desired. This can be accomplished by providing one of them with a gear 70 and providing a pinion 72 on a sliding crank shaft 71 (slidable endwise in bearings 73) so as to mesh or unmesh the 85 gears 70—72. The pulleys 31^x are mounted on stub shafts 74 on a stepped support 27^x. In this form of the invention the cable is threaded between a pair of horizontal guide rolls 65^x, then between a pair of vertical 90 guide rolls 66^x, around one of the drums 37^x, then wound alternately over the drums 6^x—6^x, every other pass of the cable around the right hand drum 6^x being continued around one of the pulleys 31^x as best shown in Figure 6, the cable continuing from the left hand drum 6^x over the other drum 37^x, thence between the adjacent pair of vertical guide rolls 66^x and thence between the other pair of horizontal guide rolls 65^x. 100

105 Referring again to the preferred embodiment of my invention (Figures 1 to 5, inclusive) it will be seen that in order to lower a heavy load down a steep incline, the machine being anchored at the top of a steep pitch or hill, through the bail 3 the load is applied to either end of the cable 75 at the front of the machine. This portion or side of the cable then becomes what I shall hereinafter term the "tight cable." The opposite end of the cable, I shall hereafter term the "slack cable" as it is slack except for its own weight. The operator, with the lever 58, applies tension to the bar 55 under leverage with a fulcrum at 59 to tighten the friction belt, strap or band 52 tending to retard the movement of the sheave 37 at the side on which the "slack cable" lies, by friction over the brake hub 38. As the shaft 36 is not movable up and down, the tension on the 110 brake band 52 tends to draw the roller 50 and drum 37 together.

115 The load is started down the hill, the "tight cable" is drawn over idle roll 65 between guide rolls 66 and over the adjacent sheave or drum 37, coming from the grooved drum 6, the speed of revolution of which drum 6 is controlled by the operator through the brake lever 12 and the brake 21—22. The "tight cable" passing around the grooves 120 130

of the drum 6 and over idle sheaves 31 comes from between the sheave or drum 37 and roller 50 on the "slack cable" side, the aforesaid operation of the brake 52 on the "slack cable" side (the brake 52 on the outgoing or "tight cable" side being released) causing the cable to be retarded by friction over the sheaves or drums 37, thereby maintaining a constant tension in the wraps and turns of the cable around the drum 6. The sheaves 31 are termed sloping sheaves and are mounted to effect a smooth transfer of the cable between the grooves of the drum 6. The drums 6 are provided with grooves so as to separate the turns of the cable to prevent binding or tangling. The "tight cable," descending with a load, hauls the "slack cable" up the hill where it takes the next load and thereby becomes a "tight cable," etc.

20 As the operation of the second embodiment of my invention illustrated in Figures 6 et seq. is quite similar to that of the first embodiment of the invention described, a detailed description of the operation of the second embodiment is believed to be unnecessary and while I have disclosed two embodiments of my invention, I nevertheless wish it understood that other modifications of the same may be made without departing from the spirit of the invention or the scope of the appended claims.

My present application is, as to all subject matter in common, a continuation of my application Serial No. 436,746 filed January 12, 1921, and through it a continuation of my application Serial No. 269,715, filed January 4, 1919.

From the foregoing description, taken in connection with the accompanying drawings, it is thought the complete construction, operation and advantages of my invention will be readily understood by those skilled in the art.

What I claim is:

45 1. In a snubbing machine, drums over which a cable is passed, pressure rollers adapted to bear upon said cable as it passes over said drums, yokes carrying said rollers, said yokes being spring pressed, means for regulating the tension of said springs, shafts carried by said yokes on which said pressure rollers are mounted, brake bands looped over said shafts, brake drums fixed to said first mentioned drums, said brake bands passing around said drums, and means for alternately tightening one brake band and loosening the other.

2. In a snubbing machine, drums over which a cable is passed, pressure rollers adapted to bear upon said cable as it passes over said drums, yokes carrying said rollers, said yokes being spring pressed, means for regulating the tension of said springs, shafts carried by said yokes on which said pressure rollers are mounted, brake bands looped

over said shafts, brake drums fixed to said first mentioned drums, said brake bands passing around said drums, means for alternately tightening one brake band and loosening the other, said means including rods to which said brake bands are connected and a lever to which said rods are connected.

3. In a snubbing machine, drums over which a cable is passed, pressure rollers adapted to bear upon said cable as it passes over said drums, yokes carrying said rollers, said yokes being spring pressed, means for regulating the tension of said springs, shafts carried by said yokes upon which said pressure rollers are mounted, brake bands looped over said shafts, brake drums fixed to said first mentioned drums, said brake bands passing around said drums, means for alternately tightening one brake band and loosening the other, said means including rods to which said brake bands are connected and a lever to which said rods are connected and compression springs over which said lever is mounted.

4. In a snubbing machine, drums over which a cable is wound, pressure rollers adapted to bear upon said cable as it passes over said drums, yokes carrying said rollers, said yokes being spring pressed, means for regulating the tension of said springs, shafts carried by said yokes upon which said pressure rollers are mounted, brake bands looped over said shafts, brake drums fixed to said first mentioned drums, said brake bands passing around said brake drums, means for alternately tightening one brake band and loosening the other, said means including rods to which said brake bands are connected and a lever to which said rods are connected, compression springs over which said lever is mounted and means whereby the free ends of said levers may be held raised or lowered.

5. In a snubbing machine, friction drums, brake drums for said friction drums and means for simultaneously braking one drum and releasing another, said drums having grooves, said means comprising friction rollers operating in said grooves and brake bands operating over said brake drums and connected with said rollers and controlling the roller pressure.

6. In a snubbing machine, friction drums, brake drums for said friction drums and means for simultaneously braking one drum and releasing another, said drums having grooves, said means comprising friction rollers operating in said grooves and brake bands operating over said brake drums and connected with said rollers and controlling the roller pressure, vertically movable rods for operating said brake bands and a pivotally mounted cross arm to which said arms are connected, said cross arm operating as a lever.

7. In a snubbing machine, friction drums, brake drums for said friction drums, means for simultaneously braking one drum and releasing another, said drums having 5 grooves and friction rollers operating in said grooves, said means consisting of brake bands operating over said brake drums, vertically movable rods for operating said bands, a pivotally mounted cross arm to 10 which said rods are connected, said cross arm having an extension to form an operating lever, and a cable threaded over said drums over which said rollers operate.

8. In a snubbing machine, friction drums 15 and means for simultaneously braking one drum and releasing another, said drums having grooves, friction rollers operating in said grooves, said means consisting of brake bands, movable rods for operating said bands, a pivotally mounted cross arm to 20 which said rods are connected, said cross arm having an extension to form an operating lever, a cable threaded over said drums over which said rollers operate, guide rollers 25 between which opposing ends of said cable pass, a guide for said cross arm extension and means cooperative with said guide whereby said cross arm may be held in any one of a number of positions.

9. In a snubbing machine, a plurality of sets of drums, a plurality of pulleys, a cable threaded around the drums and pulleys, means for supporting said pulleys in inclined positions relative to said drums and 35 friction rollers acting directly on and in cooperation with certain of said drums to form a combined braking and releasing means.

10. In a snubbing machine wherein is provided a frame, main brake drums and 40 sheaves over which a cable is threaded and wherein is provided means for applying a braking force to said main drum to retard the progress of the cable; a cable guiding and tension means through which the entering 45 and leaving ends of the cable are threaded, said guiding and tension means comprising a support, auxiliary drums on said support over which the cable ends pass, sliding frames on the support, pressure rollers 50 carried by said sliding frames and adapted to hold the cable in contact with the respective auxiliary drums, means for yieldingly holding said rollers towards their respective drums, and guide rollers for the outgoing 55 and incoming ends of the cable.

11. In a snubbing machine wherein is provided a frame, main brake drums and sheaves over which a cable is threaded and wherein is provided means for applying a 60 braking force to said main drum to retard the progress of the cable; a cable guiding and tension means through which the entering and leaving ends of the cable are threaded, said guiding and tension means comprising 65 a support, auxiliary drums on said sup-

port over which the cable ends pass, sliding frames on the support, pressure rollers carried by said sliding frames and adapted to hold the cable in contact with the respective auxiliary drums, means for yieldingly holding said rollers towards their respective drums, guide rollers for the outgoing and incoming ends of the cable, said holding means comprising brake bands, one end of each of which is connected with its respective sliding frame and devices around the brake drums carried by said auxiliary drum, and a yieldably mounted lever device connected with said brake bands for drawing the same taut.

12. In a snubbing machine wherein is provided a frame, main brake drums and sheaves over which a cable is threaded and wherein is provided means for applying a braking force to said main drum to retard the progress of the cable; a cable guiding and tension means through which the entering and leaving ends of the cable are threaded, said guiding and tension means comprising a support, auxiliary drums on said support over which the cable ends pass, sliding frames on the support, pressure rollers carried by said sliding frames and adapted to hold the cable in contact with the respective auxiliary drums, means for yieldingly holding said rollers towards their respective drums, guide rollers for the outgoing and incoming ends of the cable, said holding means comprising brake bands, one end of each of which is connected with its respective sliding frame and devices around the brake drums carried by said auxiliary drum, and a yieldably mounted lever device connected with said brake bands for drawing the same taut, said lever device having provision for loosening one brake band while simultaneously tightening the other for the purposes described.

13. In a snubbing machine wherein is provided main drums and sheaves over which a cable is wound and devices for governing the movement of the cable over said drums and sheaves; of means for holding the cable taut on said drums and sheaves, said means comprising a frame, auxiliary drums relatively fixedly mounted on said frame over which the incoming and outgoing ends of the cable pass, yokes slidably mounted on said frame, rollers mounted on shafts in bearings carried by said yokes, there being a roller 110 for each auxiliary drum, said cable passing over said auxiliary drums and being pressed by said rollers, means continuously tending to press said rollers against their respective drums and other means for applying force 115 to said rollers to force them against their respective drums.

14. In a snubbing machine wherein is provided main drums and sheaves over which a cable is wound and devices for governing 120

- the movement of the cable over said drums and sheaves; of means for holding the cable taut on said drums and sheaves, said means comprising a frame, auxiliary drums relatively fixedly mounted on said frame over which the incoming and outgoing ends of the cable pass, yokes slidably mounted on said frame, rollers mounted on shafts in bearings carried by said yokes, there being a roller 5 for applying force to said rollers to force them against their respective drums, sail last named means comprising brake drums carried by said auxiliary drums, brake bands connected with said sliding yokes and passing around said auxiliary drum brake drums, a rocking lever to either side of the fulcrum of which the respective brake bands are connected, whereby when said lever is rocked said sliding frames with their rollers 70 will be alternately moved to bring their rollers into forcible engagement with their respective drums, and a yielding fulcrum for said lever.
- 10 for each auxiliary drum, said cable passing over said auxiliary drums and being pressed by said rollers, means continuously tending to press said rollers against their respective drums and other means for applying force 75 to said rollers to force them against their respective drums, said continuously tending means comprising spring elements acting on said yokes.
- 15 15. In a snubbing machine wherein is provided main drums and sheaves over which a cable is wound and devices for governing the movement of the cable over said drums and sheaves; of means for holding the cable taut on said drums and sheaves, said means 80 comprising a frame, auxiliary drums relatively fixedly mounted on said frame over which the incoming and outgoing ends of the cable pass, yokes slidably mounted on said frame, rollers mounted on shafts in bearings carried by said yokes, there being a roller for each auxiliary drum, said cable passing over said auxiliary drums and being pressed by said rollers, means continuously tending to press said rollers against their respective drums, other means for applying force to said rollers to force them against their respective drums, said continuously tending means comprising spring elements acting on said yokes, 85 said last named means comprising brake drums carried by said auxiliary drums, brake bands connected with said sliding yokes and passing around said auxiliary drum brake drums, and a rocking lever to 90 either side of the fulcrum of which the respective brake bands are connected, whereby when said lever is rocked, said sliding frames with their rollers will be alternately moved to bring their rollers into forcible engagement with their respective drums.
- 20 20. 16. In a snubbing machine wherein is provided main drums and sheaves over which a cable is wound and devices for governing the movement of the cable over said drums and sheaves; of means for holding the cable taut on said drums and sheaves, said means 95 comprising a frame, auxiliary drums relatively fixedly mounted on said frame over which the incoming and outgoing ends of the cable pass, yokes slidably mounted on said frame, rollers mounted on shafts in bearings carried by said yokes, there being a roller for each auxiliary drum, said cable passing over said auxiliary drums and being pressed by said rollers, means continuously tending to press said rollers against their respective drums, other means for applying force to said rollers to force them against their respective drums, said continuously tending means comprising spring elements acting on said yokes, 100 said last named means comprising brake drums carried by said auxiliary drums, brake bands connected with said sliding yokes and passing around said auxiliary drum brake drums, and a rocking lever to 105 either side of the fulcrum of which the respective brake bands are connected, whereby when said lever is rocked, said sliding frames with their rollers will be alternately moved to bring their rollers into forcible engagement with their respective drums.
- 25 25. 17. In a snubbing machine wherein is provided main drums and sheaves over which a cable is wound and devices for governing the movement of the cable over said drums and sheaves; of means for holding the cable taut on said drums and sheaves, said means 110 comprising a frame, auxiliary drums relatively fixedly mounted on said frame over which the incoming and outgoing ends of the cable pass, yokes slidably mounted on said frame, rollers mounted on shafts in bearings carried by said yokes, there being a roller for each auxiliary drum, said cable passing over said auxiliary drums and being pressed by said rollers, means continuously tending to press said rollers against their respective drums, other means for applying force to said rollers to force them against their respective drums, said continuously tending means comprising spring elements acting on said yokes, 115 said last named means comprising brake drums carried by said auxiliary drums, brake bands connected with said sliding yokes and passing around said auxiliary drum brake drums, and a rocking lever to 120 either side of the fulcrum of which the respective brake bands are connected, whereby when said lever is rocked, said sliding frames with their rollers will be alternately moved to bring their rollers into forcible engagement with their respective drums.
- 30 30. 18. In a snubbing machine, a frame, means for anchoring said frame, a main cable drum journaled in bearings on said frame, said main cable drums having a series of 125 grooves to receive the cable, inclined guide sheaves for directing the cable from one groove of the drum to another, a cable wound over said drum and sheaves with its ends extending in the same general direction, a lever operating brake device cooperative with said drum to govern the movement of the cable, and a cable tensioning mechanism cooperative with said drum and sheaves and comprising a sub-frame, a 130 pair of auxiliary drums journaled in relatively fixed bearings on said sub-frame, there being one auxiliary drum for the incoming side and one for the outgoing side of the cable, each of said drums having 130

- brake drum elements movable with the same, a pair of yoke frames slidably mounted on said sub-frame, pressure rollers having shafts journaled in bearings in said yoke frames, there being one pressure roller for each auxiliary drum, vertical and horizontal sets of guide rolls in advance of said auxiliary frame over which and between which the incoming and outgoing sides of the cable pass, and means cooperative with said yoke frames for forcing one roller towards its respective drum while simultaneously releasing pressure on the other roller, and other means for applying a normal pressure to said yoke frames to thereby maintain their respective rollers in working relation to their respective drums.
19. In a snubbing machine, a frame, means for anchoring said frame, a main cable drum journaled in bearings on said frame, said main cable drums having a series of grooves to receive the cable, inclined guide sheaves for directing the cable from one groove of the drum to another, a cable wound over said drum and sheaves with its ends extending in the same general direction, a lever operating brake device cooperative with said drum to govern the movement of the cable, and a cable tensioning mechanism cooperative with said drum and sheaves and comprising a sub-frame, a pair of auxiliary drums journaled in relatively fixed bearings on said sub-frame, there being one auxiliary drum for the incoming side and one for the outgoing side of the cable, each of said drums having brake drum elements movable with the same, a pair of yoke frames slidably mounted on said sub-frame, pressure rollers having shafts journaled in bearings in said yoke frames, there being one pressure roller for each auxiliary drum, vertical and horizontal sets of guide rolls in advance of said auxiliary frame over which and between which the incoming and outgoing sides of the cable pass, and yieldable means for alternately pressing one roller towards its shaft while simultaneously releasing pressure on the other roller and vice versa.
20. In a snubbing machine, a frame, means for anchoring said frame, a main cable drum journaled in bearings on said frame, said main cable drums having a series of grooves to receive the cable, inclined guide sheaves for directing the cable from one groove of the drum to another, a cable wound over said drum and sheaves with its ends extending in the same general direction, a lever operating brake device cooperative with said drum to govern the movement of the cable, and a cable tensioning mechanism cooperative with said drum and sheaves and comprising a sub-frame, a pair of auxiliary drums journaled in relatively fixed bearings on said sub-frame, there being one auxiliary drum for the incoming side and one for the outgoing side of the cable, each of said drums having brake drum elements movable with the same, a pair of yoke frames slidably mounted on said sub-frame, pressure rollers having shafts journaled in bearings in said yoke frames, there being one pressure roller for each auxiliary drum, vertical and horizontal sets of guide rolls in advance of said auxiliary frame over which and between which the incoming and outgoing sides of the cable pass, and yieldable means for alternately pressing one roller towards its shaft while simultaneously releasing pressure on the other roller and vice versa, and other means for applying a normal pressure to said yoke frames to thereby maintain their respective rollers in working relation to their respective drums.
21. In a snubbing machine, a frame, means for anchoring said frame, a main cable drum journaled in bearings on said frame, said main cable drums having a series of grooves to receive the cable, inclined guide sheaves for directing the cable from one groove of the drum to another, a cable wound over said drum and sheaves with its ends extending in the same general direction, a lever operating brake device cooperative with said drum to govern the movement of the cable, and a cable tensioning mechanism cooperative with said drum and sheaves and comprising a sub-frame, a pair of auxiliary drums journaled in relatively fixed bearings on said sub-frame, there being one auxiliary drum for the incoming side and one for the outgoing side of the cable, each of said drums having brake drum elements movable with the same, a pair of yoke frames slidably mounted on said sub-frame, pressure rollers having shafts journaled in bearings in said yoke frames, there being one pressure roller for each auxiliary drum, vertical and horizontal sets of guide rolls in advance of said auxiliary frame over which and between which the incoming and outgoing sides of the cable pass, and yieldable means for alternately pressing one roller towards its shaft while simultaneously releasing pressure on the other roller and vice versa, and other means for applying a normal pressure to said yoke frames to thereby maintain their respective rollers in working relation to their respective drums.
22. In a snubbing machine, a frame, means for anchoring said frame, a main cable drum journaled in bearings on said frame, said main cable drums having a series of grooves to receive the cable, inclined guide sheaves for directing the cable from one groove of the drum to another, a cable wound over said drum and sheaves with its ends extending in the same general direction, a lever operating brake device cooperative with said drum to govern the movement of the cable, and a cable tensioning mechanism cooperative with said drum and sheaves and comprising a sub-frame, a pair

of auxiliary drums journaled in relatively fixed bearings on said sub-frame, there being one auxiliary drum for the incoming side and one for the outgoing side of the cable, each of said drums having brake drum elements movable with the same, a pair of yoke frames slidably mounted on said sub-frame, pressure rollers having shafts journaled in bearings in said yoke frames, there being one pressure roller for each auxiliary drum, vertical and horizontal sets of guide rolls in advance of said auxiliary frame over which and between which the incoming and outgoing sides of the cable pass, means cooperative with said yoke frames for forcing one roller towards its respective drum while simultaneously releasing pressure on the other roller, other means for applying a normal pressure to said yoke frames to thereby maintain their respective rollers in working relation to their respec-

tive drums, said last named means comprising springs and means for adjusting the tension of said springs.

23. In a snubbing machine wherein is provided a main drum and sheaves over which a cable is wound and wherein is provided means for governing the rotation of said drum; of a tensioning device through which the cable passes in moving to and from said drums, said tensioning device comprising a sub-frame, drums journaled in bearings on said sub-frame over which the incoming and outgoing sides of the cable pass, pressure rollers cooperative with each of said sub-frames, drums to hold the cable in contact therewith, means for applying braking pressure alternately to said rollers and means allowing said rollers to yield for the passage of knots and splices in the cable. 40

HENRY C. CURRIER.
